Geo. Wiedler
Letters Patent

The Invention referred to in these Letters Patent and marking part of the same containing a description in the words of the said Geo. Wiedler himself of the improvement in making a water-butt of brick, is as follows:

In the case of a cistern this apparatus for
use is as follows. First be prepared a mass of mortar in a brick-oven
made in several transverse sections about two feet long and
each transverse section in three or more longitudinal sections
fastened together by hooks, pins or other convenient means, and
capable of being taken apart, and removed at pleasure from the
place in which they are used. This cylinder or mould may be
of any length and diameter desired. Next a circular pit of any
sufficient depth is prepared in the earth, in diameter greater than
the cylinder or mould by twice the required thickness of the cistern
wall to be built.

If during the operation of excavating
such a pit the earth has flowed into the pit it may be removed by plan-
ing or other means, then a thick floor of coarse mortar is laid
all over the bottom of the pit say six inches thick upon this floor
which should be level is set one of the transverse sections of the
cylinder or mould at equal distance all around from the sides
or surface of the pit and being set it forms with the sides of
the pit a mould in which to cast the first section of the cistern
wall. If during this last operation the water has again flowed in
so as to be inconvenient, it may be again pumped out, which done
a strong mortar nearly fluid made of cement and the best sand
is cast compact between the cylinder and the sides of the pit
filling the space between them, and thus forming the first section
of the cistern wall. The water is now permitted to flow over
this section of the wall into the cistern that by its pressure it
may prevent the floor or bottom which is in an unburnt state from
being injured from the opposed pressure of the water beneath.

If the water flow in ^{the} "H" nearly or too much to retard the operation of building, it may be pumped or forced in from any river fountain. After this is done, let up on the first and proceeding therewith and in transverse section of the cylinder or mould, there as before cast in compact another quantity of cement filling the space between the cylinder and the sides of the pit thus making another section of the wall which will be of course suited to the first. Water if necessary for the purpose mentioned above may be again permitted to flow, or be pumped ⁱⁿ ~~in~~ another section of the cylinder and cylinder may at first make a cast and in section of the wall, and so continue the operation until the wall is raised to the required height. As soon as the wall is sufficiently hard the cylinder may be removed, but the water must remain until the cement is so hard as not to break by external pressure of the water, when the water flows rapidly or when it is found necessary or a better way instead of first pumping out the water and making the floor as above described, the floor may be made by settling the cement and shaping it with a common instrument on the bottom of the pit in the water. The walls also may be constructed by casting the cement in the water proceeding in all other respects as already described. Substantially as above specified this applicant makes, reserves and other effects, and covenants for however only varying the shape of the mould to suit circumstances and excavating the earth so that the sides of the pit shall correspond with that shape. The principle claimed by this applicant, is securing the bottom, and walls, of cisterns, reservoirs, and other vessels and of cellars, for keeping against, to which in a crude or unseasoned state in low-lying ground or other places, they are liable from the inflow and internal pressure of water by allowing the water as the water continues to flow into the top of cellar and thus overrunning and counteracting the external pressure of the water by the

internal weight and pressure of the same fluid. After the forming of the walls of such vessels and hollows, by casting them in a mould of which the depth is the wall of the first concrete vessel and corresponding thereto a wall made of board or other material constituting the other side.

After the sinking of the concrete and forming the bottom of the vessel, and of hollows and so much of the walls as may be necessary in the water
